UNITED STATES PATENT OFFICE.

FRANK GOTSCHE, OF SAN FRANCISCO, CALIFORNIA.

COMBINED GAME AND EDUCATIONAL DEVICE.

1,376,199.

Specification of Letters Patent. Patented Apr. 26, 1921.

Application filed July 8, 1920. Serial No. 394,736.

To all whom it may concern:

Be it known that I, FRANK GOTSCHE, a citizen of the United States, and a resident of the city of San Francisco, county of San Francisco, and State of California, have invented certain new and useful Improvements in Combined Games and Educational Devices, of which the following is a specification.

10 This invention relates to a new and useful improvement in a combined game and educational device of that type, wherein a part is revolved for the purpose of propelling game pieces so that the same may fall into 15 pockets denoting various numbers or characters.

20 The principal object of this invention is to construct a game apparatus, which may be played by a number of persons for the purpose of amusement and at the same time the 25 plays will result in educational advantage.

Another object is to produce a game apparatus which will be simple to construct and one which may be placed upon the market 25 at a reasonable cost.

Another object is to produce means whereby children will take pleasure in computing mathematical problems derived from the playing of this device.

30 Other objects and advantages will be seen as the description proceeds.

In the accompanying drawing I have illustrated one manner in which the invention may be reduced to practice, in which said 35 drawing, Figure 1 is a top plan view of my game apparatus; Fig. 2 is a cross section on the line II—II, Fig. 1; Fig. 3 is a cross section on the line III—III, Fig. 1; Fig. 4 is a top plan view of a score board; and Fig. 40 5 is a cross section on the line V—V, Fig. 4.

45 Referring to the drawings in detail, like numerals refer to like parts in the several views.

By referring in particular to Figs. 1 and 50 2, the numeral 5 represents a stationary member, having a depressed annular shoulder 6, and a circular pocket 7 formed within the margin of said shoulder 6.

A pin 8 is suitably secured in the center of the pocket 7 and is provided with a tapered end 9, which is adapted to form a

pivot point for a bearing 11. This bearing is secured in a member 12, which member is adapted to be revolved about the pin 8 and will be hereinafter referred to as the revolving member. This revolving member is so formed as to have its outer margin adjacent to the inner margin of said shoulder 6, as shown in Figs. 1 and 2.

At 13 I have shown an upstanding ring 60 formed integral with the revolving member 12 and at 14 I have shown raised portions, which form pockets around the periphery of the ring 13. Like raised portions are formed at 16 for the purpose of forming 65 pockets about the center of the revolving member.

It will be noted that the upper surfaces of the stationary and revolving member are so constructed as to slope toward the center 70 of the device, the purpose of which is to cause game pieces, such as represented by the balls 17 and 18, to move into the pockets formed by the upstanding portions 14 and 16, as shown in dotted lines at 19 and 21. 75

Upon the stationary member and adjacent the shoulder 6 I place figures here shown as reading from zero to nine, the same being equally spaced one from the other and upon the vertical space I place color marks such 80 as shown at 22—see Fig. 3.

Upon the shoulder 6 I place characters such as $\div$, $\times$, * , $+$, $-$, there being a group of these characters between every other figure of the stationary member—see Fig. 1. 85 These groups are here designated by the numeral 23.

Upon the shoulder 6 I place characters figures here shown as zero to nine. These figures are so placed as to be between the 90 raised portions 14, forming the pockets.

Upon the top of the revolving member and within the ring 13 I place characters such as stars of different colors, the same being of a number equal to the number of 95 pockets formed by the raised portions 16, which pockets are designated by a figure placed upon the top of the center portion and in this instance reads from zero to 4.

At 24 I have shown color markings, the 100 use of which will be hereinafter shown.

Referring now to Figs. 4 and 5, the same

represent a score board having pockets 26 therein, within which markers may be placed to indicate the play desired. There are preferably four of these pockets for each 5 figure, which figures correspond to those upon the stationary and revolving member and here read from zero to nine.

At the left hand end of the score board it will be noted that different colors are 10 shown so that the player may select colors, if desired.

In order to play the game, a set of cards, having tabulated thereon the value in points, is provided so that each play after being 15 made, may be quickly computed. These cards are divided into columns representing number selected, multiplication, addition, subtraction, division, star or any sign to show play.

20 A fragmentary list of the values as given on the cards is given below to illustrate the various plays which will be hereinafter given:

25	No. selected.	X	+	-	+	*	Any sign to show.					
		000	1	2	3	4	5	6	7	8	9	
30	1	500	166	166	3	500	2	500	3	500	3	
	2	166	83	4	2	500	1	500	1	500	1	
	3	166	50	7	3	500	2	500	2	500	2	
	4	83	33	10	4	500	2	500	2	500	2	
	5	250	25	16	5	500	3	500	3	500	3	
	6	62	20	25	6	500	3	500	3	500	3	
	7	250	16	41	7	500	4	500	4	500	4	
	8	55	14	33	8	500	4	500	4	500	4	
	9	100	12	250	9	500	4	500	4	500	4	
	010	125	11	10	500	5	500	5	500	5	500	5
35	1	125	11	11	500	5	500	5	500	5	500	5
	2	38	11	12	500	5	500	5	500	5	500	5
	3	125	12	13	500	6	500	6	500	6	500	6
	4	125	14	14	500	6	500	6	500	6	500	6
	5	125	16	15	500	7	500	7	500	7	500	7
	6	50	20	16	500	7	500	7	500	7	500	7
	7	125	25	17	500	10	500	10	500	10	500	10
40	048	38	48	500	20	500	20	500	20	500	20	
	9	500	49	500	41	500	41	500	41	500	41	
	050	500	50	500	45	500	45	500	45	500	45	
	1	500	51	500	50	500	50	500	50	500	50	
45	2	500	52	500	50	500	50	500	50	500	50	
	210	210	210	500	166	500	166	500	166	500	166	
	1	211	211	500	166	500	166	500	166	500	166	
	2	212	212	500	166	500	166	500	166	500	166	
	3	213	213	500	166	500	166	500	166	500	166	
	4	214	214	500	166	500	166	500	166	500	166	
50	5	215	215	500	166	500	166	500	166	500	166	

A straight play wins 5 times any sign to show play.
A play to win 5 times a sign to show.

Colors:

3 to win 125. 3 to show 20.
2 to win 25. 2 to show 4.
1 to win 5. 1 to show 2.

It will now be assumed that it is desired to play and that the winning total is to be 55 1,000, that is, the player gaining a total of 1,000 points first wins the game. It is first necessary that the player selects the play he wishes to make, *i.e.*, whether it is to be a division play, an addition play, or any of 60 the others.

To illustrate a subtraction play, the same is executed as follows:

First, the player indicates on the score board a number, for instance 8—by placing

a suitable marker in one of the pockets adjacent to the figure 8. The revolving member of the apparatus is then rotated on its pivot and the balls are caused to roll until the parts come to rest, when the balls will enter their respective pockets and we will assume that the reading is 239; then, $9-(3+2)$ equals 4 which represents a loss as it does not correspond to the reading on the score board. If it had corresponded to the reading on the score board, the player 75 would have won ten points, as will be seen by referring to the first part of the table where 4, the number selected, equals 10 in the subtraction column.

In subtraction, always subtract the sum 80 of the two small digits from the greater, or the greater digit from the sum of the two smaller so as to avoid a negative quantity.

To illustrate by multiplication:

If the product of the digits on the reading 85 after spinning equals the number set up on the score board, the player wins the number of points corresponding to that number as given in the chart above referred to.

Illustration: Indication on score board—90
5. Reading after revolving parts—209.

Then $2 \times 0 \times 9 = 0$. The player loses.

Again—indication on score board 50.

Reading 255.

Then $2 \times 5 \times 5 = 50$.

95

By now referring to the second part of the chart above given opposite 50, number selected, in the multiplication column, 500 will be found and this is the number of points that the player has won.

100

To illustrate a division play:

Indication on score board 9: Reading after revolving parts 446.

Then 9 into 446 equals 49 and 5 left over.

The player loses as it is not an even division.

Again—indication on score board 13.

Reading 221.

Then 13 into 221 equals 17—no remainder.

By referring to the chart that 13, the 110 number selected gives 13 points won in the division column.

Should the number selected correspond to the number derived from the revolving parts the player wins a number of points 115 equal to the number selected.

To illustrate star plays:

If reading is the same as the number indicated on the score board, the player wins 500 points; otherwise, he loses.

120

To illustrate an addition play:

If the sum of the digits in the reading after revolving parts equals the number indicated on the score board, the player wins.

Illustration: Indication on score board—125
20. Reading 498.

Then $4+9+8=21$. Player loses.

Again—indication on score board 0.

Reading—000.

Then $0+0+0=0$. Player wins 500 points as will be seen by referring to the table.

All of the above plays have "to show" which means that the player selected his own characters, such as multiplication, division, etc.

In order to play a "straight" play, the player sets up a number and the sign is selected by the point at which the revolving member stopped, which point is determined by the pocket into which the ball 17 falls, and by the junction of the color strip as shown at the point 27.

Illustration:

Indication on score board—213.

Reading—426, and the sign $\div$.

As 426 is divisible by 213, the player wins, and as the odds for 213 in the table, (see last section) is 166, under the column "Any sign to show" play. Had the reading been 213 and the sign a star (*), the player would have won 2,500 points.

Illustration for "Any sign to show" play.

Indication on score board, for example—13, and the reading proves to be 067, and the point 27 indicate a + (plus) the player would win. Should it be a multiplication sign, the 6 times 7 would equal 42, and the player would lose. The same is true of all the other signs.

In using the game for children no score board is used, each player taking his turn adding together on paper the differences, sums, readings, products, or the greatest prime number that will divide the reading

without a remainder. The plays are made in succession until the total amount equals a sum previously agreed upon.

For instance,

The reading 273 and the sign is — then $7-2-3=2$
The reading 431 and the sign is + then $4+3+1=8$
The reading 114 and the sign is * then $114 \times 1=114$
The reading 290 and the sign is $\times$ then $2 \times 9 \times 0=0$
The reading 323 and the sign is $\div$ then $17/323=19$

Total..... 143

40

45

Thus, it will be seen that the child will be taught to do small sums in arithmetic, which will greatly improve the mind and tend toward rapid calculation. It will also be seen that, with the older player, the game is also educational, as well as interesting, due to its element of chance.

I claim:

1. In a device of the character described, a stationary member, a revolving member, positioned within said stationary member, game pieces adapted to be moved by said revolving member and characters on said revolving and said stationary members, for the purpose of indicating plays. 60

2. In a device of the character described, a stationary member, a revolving member positioned within said stationary member, said revolving member having an upstanding ring, pockets formed adjacent said ring, 65 pockets adjacent to the center of said revolving member and within said ring, characters on said stationary and revolving members and game pieces adapted to be moved by said revolving member.

FRANK GOTSCHE.
